Primary Examiner — Kevin Rudzinski*(74) Attorney, Agent, or Firm* — Birch, Stewart, Kolasch & Birch, LLP(57) **CLAIM**

The ornamental design for an high frequency therapy equipment with graphical user interface, as shown and described.

DESCRIPTION

FIG. 1 is a front elevational view of a high frequency therapy equipment with graphical user interface showing my new design;

FIG. 2 is a rear elevational view thereof;

FIG. 3 is right side elevational view thereof;

FIG. 4 is a left side elevational view thereof; and,

FIG. 5 is a top plan view thereof.

The bottom surface forms no part of the claimed design.
The portions shown in broken lines form no part of the claimed design.**1 Claim, 3 Drawing Sheets**FIG. 1

FIG. 2

FIG. 3

FIG. 4

FIG. 5
